KNITTING & NETTING.

Knit Fabrics.

No. 11, 273.

July 1. 1879.

UNITED STATES PATENT OFFICE.

JOSEPH SIBSON, OF PHILADELPHIA, PENNSYLVANIA, ASSIGNOR TO THOMAS JONES, AARON JONES, AND JOHN E. JONES, OF SAME PLACE.

DESIGN FOR KNITTED FABRIC.

Specification forming part of Design No. **11,273**, dated July 1, 1879; application filed May 8, 1879.
[Term of patent 3½ years.]

To all whom it may concern:

Be it known that I, JOSEPH SIBSON, of Philadelphia, Pennsylvania, have produced or invented a new and original Design for a Knitted Fabric, of which the following is a specification.

My design for a knitted fabric is fully shown in the accompanying illustration.

The body A of the fabric consists of transverse cords *a*, connected together by vertical threads *b*. On this body are arranged vertical rows of loops *d*, and between the vertical rows are festoons *e*. A heading, B, is formed by discontinuing the loops *d*, and forming a continuous plain fabric topped with loops *i*.

Irrespective of the colors employed, I claim—

1. The design for a knitted fabric, said de-

sign comprising the body A, on which are arranged rows of loops *d*, all substantially as shown and described.

2. The design for a knitted fabric, said design comprising the body A, the rows of loops *d*, and the festoons *e*, all substantially as described and shown.

3. The design for a knitted fabric, said design comprising the body A, the loops, and the heading B, all substantially as shown and described.

In testimony whereof I have signed my name to this specification in the presence of two subscribing witnesses.

JOSEPH SIBSON.

Witnesses:

WILLIAM J. COOPER,
HARRY SMITH.
